HOUSING FOR HAND BRAKE WINDING MECHANISM

Filed Dec. 29, 1928 2 Sheets-Sheet 2

UNITED STATES PATENT OFFICE

RICHARD W. BURNETT, OF CHICAGO, ILLINOIS

HOUSING FOR HAND BRAKE WINDING MECHANISM

Application filed December 29, 1928, Serial No. 329,243, and in Canada February 25, 1927.

My invention relates to housings for hand-brake winding mechanisms.

The principal object of the invention is to provide an improved housing for brake winding mechanism which will be light and compact and at the same time provide great strength so as to withstand the severe strains incident to its firm attachment to a car wall and also withstand the severe stresses and pressures imparted by the winding mechanism during the brake setting operation.

Another important object of the invention is to provide a housing of such configuration that, in addition to providing strength, the plates are of such configuration that the housing may be manufactured by stamping or pressing methods, thereby insuring a high degree of accuracy in the formation of the housing members and at the same time permit them to be manufactured in large numbers at a minimum cost.

Another object is to provide a back plate which may be positioned flat against the wall of a railway car and which, when so applied, will provide a relatively large attaching base whereby the stresses developed during the brake setting operation will be distributed over a large area of a car wall.

A still further object is to provide novel reinforcements of the front and back plates at the points where the members of the winding mechanism are attached to or supported by the housing.

My invention is illustrated in two specific embodiments in the accompanying drawings wherein:

Fig. 1 is a vertical cross section of a hand brake winding mechanism attached to a railway car and showing the various operating parts of the winding mechanism supported within a housing constructed in accordance with my invention.

Fig. 2 is a cross section taken on line 2-2 through the car wall and housing, the operating parts of the mechanism being omitted from this figure.

Fig. 3 is a front face view of my improved housing illustrating the same as attached to a railway car wall.

Fig. 4 is a view similar to Fig. 3, but illus-

trating a modified construction of the housing, and

Fig. 5 is a vertical section taken on line 5-5 of Fig. 4.

Referring first to Figs. 1 to 3 inclusive of the drawings. The winding mechanism illustrated is preferably the same as that illustrated in my copending application 229,967, filed October 31, 1927, and of which the present application is a continuation in part.

The winding mechanism may be described briefly as consisting of a large gear and winding drum 10 rotatable about a horizontal shaft 11 and meshing with a pinion 12. The pinion 12 is preferably formed integrally with a shaft 13 and a ratchet wheel 14. The shaft 13 projects out of the enclosing housing and is provided at one end with an operating hand wheel 15. The numeral 16 designates a locking pawl formed with suitable trunnions 17 for supporting it in a position to engage with the teeth of the ratchet wheel 14. The pawl 16 is moved to its holding and also to its releasing position by means of a cam 18 adapted to be operated by a lever 19.

The improved housing, in which the operating parts of the mechanism above described are enclosed, consists of a back plate 20 and a dished front member 21 provided with a flange 22 for attachment to the back plate. The front and back plates are formed with oppositely disposed openings 23, 24, 28 and 29 for the reception of the several shafts of the winding mechanism. The openings 23-23 receive reduced portion 27 of the shaft 11. After the winding drum is applied, the reduced ends of the shaft 11 are preferably riveted over so as to clamp the front and back members of the housing against the shouldered end portion of the shaft. The front and back members of the housing are preferably pressed inwardly adjacent the openings 23 so as to provide inwardly projecting bosses 23^a which serve to provide suitable abutments for spacing the unitary gear and winding drum from the opposite sides of the casing. The inwardly pressed bosses also serve as reinforcements of the

85

90

95

front and back members adjacent the openings for the shaft 11, and also provide suitable pockets for the riveted over ends of the shaft. With this construction the back plate 20 may be positioned flat against the end wall 25 of the railway car without danger of the shaft 11 interfering with said flat bearing against the car wall. The depression 23^a in the front face of member 21, in addition to providing an inwardly extending boss, prevents the end of the shaft 11 from projecting out beyond the front face of the member 21. The openings 24 receive the operating shaft 13 and are formed with the inwardly projecting bosses 26. Preferably bearings 24^a are fitted in the openings 24, the said bearings being of cast bronze or any suitable bearing material. The inwardly projecting bosses 26—26 permit the outer faces of these bearings to be disposed within the outer planes of the back and front members. The openings 28, 29 receive the trunnions of the pivoted pawl 16 and the cam 18, respectively. The back plate only is formed with inwardly pressed bosses surrounding these openings so as to provide suitable clearance for the heads of the said trunnions. The housing is attached to the side wall 25 of the car by means of suitable bolts 30 extending through the flange 22 in the marginal portion of the back plate. Preferably the attaching flange is relatively narrow so that a large portion of the clamping pressure incident to attaching the housing to a car wall is taken up by the trussing effect of the side walls 31 of the dished front member. The double thickness of metal at the point of attachment of the flanges, together with the angular walls 31 of the front member, provide sufficient rigidity to prevent distortion of the housing when it is clamped to an irregular surface of the car wall. The angular construction of the housing makes it possible to use sufficient force in attaching it to a car wall, for example a sheet metal car wall, to force the surface of the wall to conform with the attaching flange of the housing, thereby avoiding distortion of the housing and the attending mal-alignment of the shaft bearings and other operating parts of the winding mechanism. In this connection it will be noted that the housing formed in the manner above noted, makes it possible to use the housing itself as a supporting frame for the operating mechanism therein enclosed.

In Figs. 4 and 5, I have illustrated a modified construction of housing. This form of the invention is in all respects the same as that previously described except that the front member of the housing is provided with a series of reinforcing and rigidifying corrugations 32 which extend radially from the inwardly pressed boss 33 surrounding the drum shaft opening 33^a. These reinforcing corrugations are preferably pressed

outwardly from the sheet. The said corrugations terminate preferably near the side flange of the housing so as to provide in effect a reinforcing beam extending entirely across the housing. The lower portion of the housing is reinforced by a transversely extending reinforcing corrugation 34, which extends entirely across the front face of the front member of the housing. This corrugation reinforces the lower margin of the front member adjacent the open lower end of the housing. This embodiment, like the form previously illustrated, is provided with assembling rivets 35 for holding the front and back members in their proper position before the winding mechanism is applied. This embodiment is shown with the back plate 20 attached directly to a sheet metal wall 25^a of the car. This manner of use, however, is common to both forms of the invention. In other respects, the modified construction may be and preferably is the same as the construction shown in Figs. 1 to 3 inclusive.

This application is a continuation in part of my application Serial No. 229,967, filed October 31, 1927, which latter application is a division of my application Serial No. 109,061, filed May 14, 1926. The present application, however, does not claim, apart from the housing structure, the holding and releasing mechanism per se; the combination of the winding mechanism and holding and releasing mechanism; the combination of the vertical hand wheel and winding drum; and the combined gear and winding drum. The mechanisms and devices above noted are claimed in the order above mentioned in my copending applications as follows: Serial No. 229,967, filed October 31, 1927; 281,088, filed May 28, 1928; 349,817, filed March 25, 1929; and 349,818, filed March 25, 1929.

I claim:

1. In brake operating mechanism comprising a chain, a winding member and gearing therefor, and pivoted holding and releasing devices; a housing to enclose said winding member and gearing devices comprising a pressed steel front plate, a pressed steel back plate, one dished to provide a mechanism compartment open at one end to accommodate lateral movement of the chain and formed intermediate its ends with outwardly curved side walls conforming to the general contour of a part of the gearing, and flanges merging into said intermediate curved portion, said plates being formed with oppositely disposed bearing openings for the shafts of said winding member and said gearing therefor and formed with inwardly projecting bosses through which said bearing openings are made, one of said plates being formed with reinforcing ribs extending radially from one of said bearing openings.

2. In brake operating mechanism comprising

ing a chain, a winding member and gearing therefor, and pivoted holding and releasing devices; a housing to contain said winding member and gearing devices comprising a
5 pressed steel front plate, a pressed steel back plate, one being of a configuration open at one end dished and provided with a flange extending around three sides thereof for attachment to the other, said plates being
10 formed with oppositely disposed bearing openings for the shafts for said winding member and said gearing therefor and formed with inwardly projecting bosses through which said bearing openings are
15 made, the dished plate being formed with side walls, portions of which are parallel with each other and portions of which are curved outwardly to provide clearance for the gearing, the front side of said dished plate being
20 formed with pressed reinforcing ribs extending radially from one of said bearing openings.

3. In hand brake operating mechanism comprising winding means and means for holding and releasing said winding means, a housing for enclosing said mechanism and providing a supporting frame therefor comprising front and back plates, one of said plates being pressed to form a mechanism
25 chamber of dished configuration open at one end and having vertical side walls curved to conform generally with the shape of parts of said mechanism, the opposite ends of said
30 dished portion being of less width than the intermediate portion so as to provide attaching flanges which taper in width toward the maximum width of said dished portion, and a reinforcing rib formed along said open end to rigidify the dished portion against distortion adjacent said open end.

4. In hand brake mechanism for railway cars including revoluble elements for applying and for releasing the brakes; a housing in which said revoluble elements are journaled comprising a back plate providing a large bearing area for attachment to a wall of the car, a front plate dished outwardly to provide a compartment for said revoluble elements open at the bottom, flanges at the sides
45 of said dished structure for attachment to the back plate, the lower portion of said dished structure being bulged laterally to provide said chamber with an enlarged portion, the curved walls of which serve as reinforcing and stiffening elements for the side attaching flanges and for the said dished portion of the plate.

RICHARD W. BURNETT.
